UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

CHARGING DEVICE

Application filed February 24, 1930. Serial No. 430,860.

This invention relates to charging devices, but more particularly to a device for depositing explosive material into a submerged drill hole.

5 One object of the invention is to facilitate the operation of depositing the explosive material in the drill hole and another object is to utilize the rock drill guide frame of a submarine drilling apparatus for guiding the 10 charging device into the drill hole.

Other objects will be in part obvious and in part pointed out hereinafter.

In the accompanying drawings illustrating the invention and in which similar reference characters refer to similar parts,

15 Figure 1 is an elevation partly in section of a submarine drilling apparatus and showing the charging device suspended between the members comprising the guide frame of 20 the drilling apparatus,

25 Figure 2 is an enlarged view of the charging device showing the manner in which the guide arms cooperate with the guide frame for guiding the container to the drill hole, and

Figure 3 is a transverse view through Figure 2 on the line 3—3 looking in the direction indicated by the arrows.

Referring to the drawings, and at first more 30 particularly to Figure 1, A designates a scow or barge upon which is mounted a submarine drilling unit designated generally by B. The unit B comprises a spud C which is shown extending through the water D and into the 35 over-burden or silt E overlying the rock F and has the usual parallel members G which carry at their lowermost end a foot piece H.

In addition to its function of acting as an anchoring means for the barge A the spud 40 C also serves as a guide for a guide frame J which comprises a pair of parallel members K and upon which the drilling apparatus, such as a rock drill L, may be slidably mounted. The portion of the spud C extending 45 above the barge A may be supported by means

of a derrick O and suitable devices (not shown) may be mounted on the derrick or on the barge for raising and lowering the spud as well as the rock drill L and its guide frame J.

50 As is customary in apparatus of this type, the guide frame J is provided at its lower end with a cross head P to which is secured a sand pipe Q adapted to be driven through the silt E to seat against the face of the rock F. The sand pipe may, as illustrated, also be guided by the foot piece H and has a funnel-shaped portion R at its upper end to conveniently guide a working implement, such as a drill steel (not shown) to a point 55 on the rock F where it is desired to drill a hole such as that designated by S. By seating the sand pipe Q directly against the rock face the cuttings resulting from the drilling operation may be readily flushed from the 60 drill hole S and the sand pipe Q will prevent the entrance of silt into the drill hole.

65 The above described apparatus may be of a well known type and has been herein only briefly described in order that the invention 70 which will be subsequently described and its use in connection with the elements of the drilling apparatus therewith may be more fully understood.

75 In removing rock from submerged beds it is customary, after the drill hole has been completed to charge the drill hole S before moving the apparatus to a new site even though the charge is not exploded until other series of holes have been drilled. One reason for immediately charging the holes is that by maintaining the spud and sand pipe in the positions which they occupy during drilling less groping is required to insert the explosive material in the drill hole than would be the case were the spud withdrawn and only the approximate location of the drill hole known.

80 85 85 Various means have been devised heretofore to serve as containers for introducing 90

the explosive material into the drill hole. One well known device of this character consists of a tubular container having a handle extension rigidly attached thereto. The explosive material is placed in the container and the container is then guided manually into the sand pipe Q. This method of charging the drill hole has been found to be successful only where the water overlying the material to be blasted is shallow and dormant. Where the barge lies at a considerable height above the sand pipe, and in locations where the current of the water is comparatively rapid, this mode of charging the drill hole is extremely difficult. As will be readily apparent the charging device may in any event be guided only from the surface of the barge and where the current of the water is strong the device is readily deflected, thus making it an extremely difficult matter to enter it into the sand pipe Q.

The present invention contemplates the elimination of these difficulties and to this end is provided a container T, preferably of tubular form, having a chamber U therein for the reception of the explosive material V. The chamber U may be of a diameter to readily receive the explosive material which may be conveniently retained within the chamber by an exploder wire W secured to the foremost piece of explosive material and leading upwardly to the deck of the barge A.

One end of the wire W is of course connected to a detonator X in the explosive material V, and by maintaining the wire W reasonably taut and paying it out as the container T is being lowered the explosive material will be readily retained within the container T. The container may be provided with a slot Y for the accommodation of the wire W.

To the end that the guide frame J may be used as a means for guiding the container T into the sand pipe Q and thus to the drill hole S, the said container is provided with a pair of bearings Z and b having pivotally mounted thereon guide arms c and d respectively. The bearing Z may be fixedly secured to the end of the container T, and the bearing b is provided with a bore e of somewhat larger diameter than the diameter of the container T so that said bearing may slide freely on the container.

The guide arms c and d may be similar in all their essential respects and each guide arm is provided at its ends with slots f for slidable engagement with the inner edges of the parallel members K.

Suitable means are provided to maintain the guide arms in engagement with the members K. The means provided for this purpose consists of bolts g disposed in slots h in the guide arms and adapted to be moved into slots j in the bearings. The slots j and h are

so arranged that they will register with each other when the guide arms occupy positions perpendicular to the container T, and on the bolts g are threaded wing nuts k whereby the bolts g may be conveniently clamped in position.

Being slideable on the container T, it is desirable that the bearing b and the guide arm d be restrained against accidentally sliding from the container T. Convenient means are provided for this purpose in the form of a pair of cables o which are attached at their ends to both the guide arm c and the guide arm d and preferably near the ends of the said guide arms. The arrangement is such that when the charging device is disposed between the parallel members K and the guide arms are in engagement with said members the guide arms d will be held in spaced relation with respect to the guide arms c by the cables o.

The charging device is preferably supported by a cable p which may extend upwardly along the derrick O to overrun a sheave (not shown) and having a return portion q to which may be attached a counterweight r to retain the device in the various positions in which it may be placed and also to relieve the operator of the strain of lifting and lowering the device. The cable p carries a hook s upon which is hooked a loop t in a cable u which is attached with its ends to the guide arm c. An additional loop v may be provided in one of the sections of the cable u and said loop v is adapted to be placed on the hook s to hold the guide arms in an inclined position wherein they will be out of engagement with the parallel members K.

As may be readily observed the container T is open at both ends. This permits the explosive material to be entered from the front end of the chamber U and by providing a similar opening at the opposite or upper end of the container the means, such as a wash pipe w, may be readily disposed in the said container to subject the explosive material V to water under pressure for expelling the said explosive material from the chamber U.

When not in use the wash pipe w may hang suspended along the guide frame J and the upper end thereof may be attached to a cable x which may be suitably trained over a sheave (not shown) on the derrick O. On the opposite or depending end y of the cable x may be attached a counterweight z. Pressure fluid may be supplied to the wash pipe w by a flexible conduit 2 leading from a source of pressure fluid supply and connected to a point near the upper end of the wash pipe.

The operation of charging the drill hole S by means of the charging device described herein is as follows: After the drill hole S has been completed the drilling apparatus, such as the rock drill L, may be raised and the working implement may then be removed.

The guide frame J and the sand pipe Q however, remain in the positions which they occupy during the drilling operation. The charging device together with the explosive

material in the container T may then be moved between the parallel members K of the guide frame J. Thereafter the guide arms c and d may be rocked into position to enable the slots f in the ends of the guide arms to engage the members K whereupon the bolts g may then be moved into the slots j and by tightening the nuts k said bolts will remain securely in position to hold the guide arms in the guiding position.

15 With the parts thus arranged the container T will occupy substantially the same position previously occupied by the working implement of the rock drill L. The device may then be lowered and the entrance of the container T into the sand pipe Q and the drill hole S may be effected without difficulty.

As the container T is lowered the bearing b of the guide arm d will seat upon the top of the sand pipe Q and the container may then 25 slide through the bearing b until the bearing Z in turn seats upon the bearing b, or until the container has entered the drill hole S to the desired depth.

When this position of the container T has 30 been reached the wash pipe w may be lowered and entered in the upper end of the chamber U. Water under pressure may then be admitted into the container and the explosive material V will be ejected thereby and forced 35 into the bottom of the drill hole S.

After ejecting the explosive material from the container the charging device may be raised until access may be had to the guide arms. The bolts g may then be removed from 40 the slots k and the loop v may be hooked on the hook s. In this way the guide arms will again be moved out of engagement with the parallel members K so that the charging device may be readily removed from the path 45 of the rock drill L.

I claim:

1. In a charging device for drill holes, the combination of a support and parallel members thereon to form a guide frame, means 50 forming a container for explosive material, and means secured to the container and cooperating with the guide frame to guide the container to the drill hole.

2. In a charging device for drill holes, the 55 combination of a support and parallel members thereon to form a guide frame, means forming a container for explosive material, and means carried by the container and being movable into slidable engagement with the 60 guide frame to guide the container to the drill hole.

3. In a charging device for drill holes, the combination of a support and parallel members thereon to form a guide frame, means 65 forming a container for explosive material,

and means pivotally secured to the container and being adapted to slidably engage the guide frame for guiding the container to the drill hole.

4. In a charging device for drill holes, the 70 combination of a support and parallel members thereon to form a guide frame, a container for conveying explosive material to the drill hole, and a plurality of means spaced with respect to each other along the length of the container and being adapted to slidably engage the guide frame for guiding the container to the drill hole.

5. In a charging device for drill holes, the 75 combination of a support and parallel members thereon to form a guide frame, a container for conveying explosive material to the drill hole, and a plurality of means spaced with respect to each other along the length of the container and being adapted to slidably engage the guide frame for guiding the container to the drill hole, and a bearing 80 for one of the said means disposed slidably on the container.

6. In a charging device for drill holes, the 85 combination of a support and parallel members thereon to form a guide frame, a container for conveying explosive material to the drill hole, a bearing affixed to the container, a second bearing disposed slidably on the 90 container, and arms pivoted on the bearings and being adapted to engage the guide frame for guiding the container to a drill hole.

7. In a charging device for drill holes, the 95 combination of a support and parallel members thereon to form a guide frame, a container for conveying explosive material to the drill hole, a plurality of bearings, one of said bearings being affixed to the container and another of said bearings being disposed 100 slidably on the container, guide arms pivotally mounted on the bearings, means on the ends of the guide arms to slidably engage the guide frame, and means connecting the guide arms whereby one guide arm supports the 105 other guide arm and its bearing.

8. In a charging device for drill holes, the 110 combination of a support and means thereon to form a guide frame, a container for conveying explosive material to the drill hole, a fixed bearing at one end of the container, a movable bearing freely slidable on the 115 container, guide arms pivotally mounted on the bearings and being adapted to slidably engage the guide frame for guiding the container to the drill hole, flexible means connecting the arms, and means for locking the side arms fixedly to the bearings.

9. In a charging device for drill holes, the 120 combination of a support and means thereon to form a guide frame, a sand pipe interposed between the guide frame and the material intended to be blasted and in axial alignment with the drill hole, a container for conveying 125 explosive material to the drill hole and 130

adapted to pass through the sand pipe, a fixed bearing at one end of the container, a movable bearing freely slidable on the container, guide arms pivotally mounted on the bearings and being adapted to slidably engage the guide frame for guiding the container into the sand pipe and thus into the drill hole, cables connecting the guide arms to support the movable bearing and the guide arm pivoted thereon, and means for locking the guide arms to the bearings.

In testimony whereof I have signed this specification.

CHARLES C. HANSEN.
